In Italy April 27, 1938

8 Claims. (Cl. 218—19)

The invention relates to devices for applying rivets and more particularly for forming rivet connections between bodies, one of which may be hollow and inaccessible.

The invention solves the problem in the simplest way and consists essentially in this, that it makes use of a striking hammer-like riveting tool extending for only a small portion of the periphery of the free end of the rivet and that in the beading operation it revolves around its axis so as to operate gradually over the whole periphery of the bush.

But in another embodiment of the invention, one might just provide pressure, always accompanied by the characteristic rotation, automatic or non-automatic, so that the rivet end may be flared gradually and upset against the inner wall.

The invention will now be disclosed with reference to the attached drawings, given solely as example of an embodiment, limiting in no way the range of the invention.

In the drawings, the first two figures are given just to explain the method, whilst the remaining figures show an embodiment of a hand apparatus, based on the beading-action of a hammer using a spring drive and with angular automatic displacements obtained step by step by a ratchet wheel. Namely:

Fig. 1 is a vertical section through a rivet and cooperating tool portions, showing the riveting action obtained within an inaccessible chamber;

Fig. 2 is a plan view of the same with the upper portion of the chamber omitted.

Fig. 3 is a perspective view of the tool for performing the riveting;

Fig. 4 is a vertical section through the central portion of the tool, according to Fig. 3.

Fig. 5 is a detail vertical section taken substantially on line 5—5 of Fig. 4;

Figs. 6 and 7 and 8 are detail cross sections, taken respectively along lines 6—6, 7—7, and 8—8 of Fig. 4;

Fig. 9 is a detail vertical section on a larger scale through the riveting hammer.

With reference to Figs. 1 and 2: A is the comparatively inaccessible hollow member to be riveted to B by means of hollow rivets 10, having an axial hole 11 for permitting passing into it the riveting tool or hammer 12 and a guiding bar 13. These slide within a sleeve 14, upon which the head 15 of the rivet bears. If a rotation is given to the riveting tool around its axis, combined with a reciprocating hammering motion along the same axis, the edge of the hollow-rivet 10 is beaded or upset by the hammer 12 towards the out-

side thereby securing the two members. In order to start riveting, first the riveting hammer 12 is introduced in hole 11, the guide-bar 13 having been displaced relatively to the hammer 12. The riveting tool 12 is provided with a lateral projection 12a designed so as to freely go through hole 11 of hollow-rivet 10. The guiding-bar 13 is then moved to operative position in the hole and riveting is begun. In a reverse order of movements the riveting tool 12 can be removed. Figs. 3 to 9 show an embodiment of the riveting device. This has two handles 20, 20a fixed to the outer body of the apparatus. Under one of said handles projects a working-lever 21, whilst under the other handle is placed a lever 22 for lifting the bar 13 to inoperative position. Lever 21, besides controlling the reciprocating movement of the riveting tool 12, provides for its rotation so as to move the hammer to operate over the whole periphery of the free end of the hollow rivet. Besides said lever is held in raised inoperative position as soon as the riveting action is terminated, namely, when the riveting hammer 12 has completed a revolution and is also combined with means for adjusting the stroke of the tool 12, according to the length of the rivet and the thickness of the articles to be united. Lever 21 is fulcrumed at 23 (Figs. 4 and 6) and has two hinged arms 24, pressed toward each other by springs 25, which tend to keep said arms engaged in an annular groove cut in the tube 27 just above the flange 26. Tube 27 encloses the riveting hammer and its guide-bar 13. Arms 24 (Fig. 6) carry on their ends revolving balls or rollers 28 for reducing friction between the moving parts during reciprocating movement thereof and also for cooperating with a wedge 29 which, on getting between said arms 24 during the action of lever 21, compels them to swing outwardly, thus disconnecting tube 27 from said arms 24 and permitting said tube to perform its working stroke. The wedge 29 ends with a threaded stem 30, sliding in a stationary collar 31 and cooperating with a screw 32 provided with an adjusting knob 33 projecting outside of the casing. On the threaded stem 30 is fixed an index 34 cooperating with a graduated scale on the outside of the casing, the setting of the index relative to said scale depending on the thickness of the plates to be united and on the material of the rivets.

To lever 21 is pivoted one end of link 35, (Fig. 4) the other end of which is pivoted to a lever 36 fulcrumed adjacent its upper end, at 37, to the body of the apparatus and said lever is pro-

vided at its lower end with an extension 38, pivoted at 39 (Fig. 5) to lever 36 and normally pressed inwardly by a flat spring 40, whereby said extension 38, by lateral swinging can also assume the position 38' shown in dotted lines in Fig. 5. A ratchet wheel 41 is slidably keyed on the tube 27 by means of a key seating in a longitudinal key-way 41' (Fig. 8), cut in said tube so as to allow it axial motion. The ratchet-wheel 41 is rotated by lever 21 through link 35, lever 36 and its extension 38, which, by engaging the teeth of the ratchet wheel moves it through a predetermined angle (herein shown as 60°) for each full upward swing of the lever 21, the magnitude of swing of lever 21 depending upon the adjustment of wedge 29. The ratchet-wheel is also pressed upon by a resiliently mounted brake 42 (Fig. 6), which, by pressing against the teeth of said wheel, prevents accidental rotation of the wheel. Lever 22 is fulcrumed at 43 (Fig. 4) to a downwardly extending member 44 also operating as a stop to the upward movement of the inner end of lever 21. The lower end of a small link 45 is pivoted on lever 22 substantially midway of its length and carries on its upper end a pawl 46 which is pressed downwardly by a spring 47 to compel the pawl 46 to cooperate with crown 48 of a sleeve 49, concentric with tube 27 (Fig. 9). Inside of said sleeve 49 is fitted a bolt 50 provided with a head 51, which is normally held against the internal shoulder 49a of the sleeve 49 by means of a helical spring 52, encircling bolt 50. Bolt 50 has, at its lower end, a projection 53 retaining a ring 54 which is pressed also by spring 52 against said projection 53. In said bolt 50 there is cut a notch for receiving the end 55 of the bar 13, provided with a retaining projection 56 (Fig. 9).

The sleeve 49 is herein shown as slidably fixed in a bushing 57, pressed toward the upper end of tube 27 by the action of spring 52 and coaxial with tube 27. On the mouth of this tube 27 a projection 27a is provided for holding a bushing 58 which is pressed against said projection 27a by a second helical spring 59 concentric with spring 52. Projection 27a is provided with a cavity 60 through which end 61 of the riveting hammer 12 passes, said end 61 being secured to bushing 58 by a projection 62 so that said end 61 and the riveting hammer moves with tube 27. The guide bar 13 is displaceable, however, independently of the riveting tool 12 against the tension of the spring 52. Bushing 57 carries pins 63 (Fig. 9), which form a bayonet fixture with grooves 64 cut in the inner periphery of tube 27, being maintained normally in the upper ends of said grooves by the action of spring 59. Lever 22 is also provided with a small roller 65 (Figs. 4 and 7) carried by links 66 and which can engage a finger 67 carried by lever 21 and move said finger away from the tube 27. Said pawl 67 is pressed inwardly by a spring 68 and engages at the completion of a riveting operation in a notch 69 (Fig. 9) in tube 27. The notch is at such a height that, at the end of a riveting operation, it is engaged by the finger 67 to prevent the lever 21 from fully returning to its initial position. Roller 65 rolls on an inclined surface 70a provided on the lower end of a sleeve 70 encircling the upper end of tube 27, so as to be displaced laterally, the sleeve 70 being fixed to the body of the apparatus by a nut 70b. Lever 22 carries spaced extensions 71 (Figs. 4 and 7) united by a cross-bar 72, which bar forms a stop for limiting movement of a fork 73.

5 pivoted at 43 and pressed by a spring 74 against the stop bar 72. Said fork 73 is moved under certain conditions, as will be disclosed hereinafter, into the path of a stop 75 (Fig. 6) pivoted at 76 to lever 21, and normally held in the position shown in Fig. 4 by torsion spring 77. The engagement of the fork 73 with the stop 75 limits the preliminary movement of the lever 21 incident to which the tool 12 is inserted in the rivet. The 10 apparatus is completed by a driving spring 78 (Figs. 4 and 5), encircling tube 27 and by the lower guiding bushing 79, ending in a threaded projection 80, to which is secured the sleeve 14, which in use bears against the rivet's head.

15 In order to perform the riveting, first the riveting device is operatively positioned with respect to the rivet, by means of the operation of levers 21 and 22. By pressing on the latter as far as it will go and holding it there, the tooth 46 engages crown 48 of bushing 49 and lifts it. The lifting of crown 48 pulls up bushing 49 and the shoulder 49a in turn pulls up head 51 and rod 50. The projection 53 on rod 50 moves up with rod 50 and in so doing lifts ring 54 against the tension of spring 52. The upward movement of rod 50 lifts the guide bar 13 carried by rod 50 and the swing of lever 22 lowers the fork 13 into the path of the stop 75. Then due to clearance provided between the fork 13 and stop 75 the riveting tool is partly pushed out and passes through the hole of the rivet. This movement of tool 12 is effected thus: the movement of the lever 21 moves the arms 24, and the rollers 28 on said arms abut against the flange 26 on the tube 27 and moves said tube outwardly through guide bushing 79 against the force of spring 18. During such outward movement of tube 27 the spring 59 holds the bushing 58 against the projection 27a and the projection 62 engaging the notched end 61 of the tool 12 effects outward movement of said tool. Upon release of the lever 22, the guide-bar 13 also enters in the rivet's hole under the action of the spring 52 and upon release of the lever 21 tube 27 is pushed inwardly by the spring 78, the parts 12 and 13 being brought to the position shown in Fig. 1 except that part 12 is held by engagement of hook 12a with the uncollapsed rivet. The purpose of the fork 73 is to avoid undue resistance to return of the lever 22 and permit it to freely return to initial position following an operation thereof. Said fork is normally held against the cross bar 72 by the spring 74 and is retained in this position while the lever 22 is held raised and the lever 21 is subsequently lifted to partially project the tool 12 as above described. After the tool 12 has been properly inserted in a rivet the lever 22 is released and returns to operative position. In so doing, said lever turns about the pivot 43 freely while the fork 73 is held in its position of engagement with the stop 75 until the lever 21 is released and restored to its initial position whereupon, the pressure between the elements 75 and 73 being released, 60 the fork 73 is restored to a position in engagement with the cross bar 72 by the tension of the spring 74. The spring 77 coacting with the stop 75 permits movement of the latter relative to the lever 21 to avoid jamming between the elements 73 and 75. Lever 21 then will swing freely and its arms 24 will move the tube 27, thus compressing the driving spring 78.

65 On lowering sufficiently, arms 24 engage the wedge 29, which, due to its shape and position, 70 will spread said arms apart, thus disconnecting

them from flange 26 and allowing the quick return of the tube 27 under the action of spring 78. Thus the riveting tool 12 on its return stroke, causes the upsetting of a part of the projecting tail of the rivet. Upon lever 21 being released rolls 28 ride up along spring 78 and past flange 26 to the top thereof and in position to again depress flange 26. During this upward movement of rolls 28 finger 67 also moves upwardly, spring 68 tending to hold it in contact with tube 27 during such upward movement. During each stroke but the last one finger 67 moves to the top of its stroke, since notch 69 was moved out of line with finger 67 by the partial movement of lever 21 incident to inserting tool 12 into the rivet. However, upon the completion of the riveting the notch 69 has returned to a position in line with finger 67 and said finger is caught by said notch before it has completed its upward movement. This holds the handle end of lever 21 in partially elevated position, thus affording an indication that the riveting is completed.

When lever 21 was swung, lever 36 was displaced so that its pivoted end portion 38 is actuated, engaging and imparting a rotary movement to the ratchet wheel 41, rotating with it the tube 27 to which it is keyed and the parts 12 and 13. In this way the hook 12a of the riveting tool 12 on successive strokes engages the whole circumference of the rivet's tail, without requiring any hand-rotation of the riveting device, and obtaining at each stroke of the lever 21 the upsetting of a new part of the rivet, so that after a number of strokes the riveting is completed. In the case illustrated, the ratchet wheel 41 having six teeth, the riveting is completed after six strokes. As soon as this is completed the tube 27 reaches such a position in its rotation that finger 67, carried by lever 21, engages in notch 69, to hold the handle end of the lever 21 in raised position, thereby indicating that the riveting operation is completed and the riveting device is ready to be removed. To do this the operator presses lever 22 and holds it pressed, which besides lifting guide-bar 13 in the manner described above, disengages the finger 67 from the notch 69 by means of roller 65. On pressing the lever 21, the riveting tool 12 is pushed out partially, as stated above and may then be removed from the rivet, and the cycle of operations described above may be repeated with another rivet.

Springs 52 and 59, placed inside tube 27, besides maintaining the members acted on thereby in proper position also perform a safety function. Whenever the riveting tool 12 and the guide-bar 13 should encounter, on being inserted into the rivet, an obstacle preventing them from being completely inserted, the tool 12 together with its bushing 58 and the guide-bar 13 together with its ring 54 are repressed into the tube 27 against the pressure of the springs 59 and 52 respectively. Thus, the tools 12 and 13 are protected from breakages in that upon meeting with an obstacle they can reenter the tube 27, compressing springs 52 and 59.

It is evident that the replacement of the riveting tool 12, the guide-bar 13 and the sleeve 14, to fit different diameters of rivets, is quite simple. To replace these parts the sleeve 14 is removed and the tube 27 temporarily held against rotative and downward movement with known means. Then the user will press down on bushing 49 with a screw-driver or like tool and turn bushing 49 so that pins 63 are in line with the vertical parts of

bayonet slots 64. The springs 52 and 59 will then push the bushing 49 out of the tube 27. Thus the whole mechanism mounted in tube 27 may be taken out and the riveting tool 12 with its guide-bar 13 can be easily replaced.

Notwithstanding our having specified and illustrated a practical embodiment of the invention, the construction may vary. It is to be understood that, in practice, the design and construction may vary within the limits of the invention.

Having now described our invention and how the same is to be carried out, what we claim as our invention is:

1. A device for flanging hollow rivets comprising a guide member, a riveting tool axially movable in said guide and having a lateral projection adapted to be passed through a hollow rivet for engaging and flanging a portion of the free edge thereof at each axial movement of the tool toward said edge, means for imparting successive independent swift hammer-like axial movements to the tool in the direction of the rivet and means controlled by the first mentioned means to rotate the tool about its axis between each of said axial movements thereof to render the projection operative upon successive portions of said free edge.
2. A device for flanging hollow rivets comprising a guide member, a riveting tool axially movable in said guide member and having a lateral projection adapted to be passed through a hollow rivet for engaging and flanging a portion of the free edge thereof at each axial movement of the tool toward said edge, said tool being rotatable in said guide member to render said projection operative upon successive portions of said free edge, and means for imparting a swift hammer-like axial movement to the tool in the direction of the rivet, said means including a spring normally urging the tool towards the rivet, and manually controlled trip means for compressing the spring and releasing said tool.

3. A device as claimed in claim 1 characterized in that said movement imparting means includes a spring normally urging the tool towards the rivet, and manually controlled trip means for compressing the spring and releasing said tool.

4. A device for flanging hollow rivets comprising a guide member, a riveting tool axially movable in said guide and having a lateral projection for engaging and flanging a portion of the free edge of the rivet at each axial movement of the tool toward said edge, spring means normally urging the tool toward the rivet, a member normally lying adjacent the tool and displaceable relatively thereto, manually controlled trip means for compressing said spring and releasing said tool for actuation under the influence of said spring, and manually controlled means for displacing the second mentioned member.

5. A device for flanging hollow rivets comprising a guide member, a riveting tool axially movable in said guide member and having a lateral projection for engaging and flanging a portion of the free edge of the rivet at each axial movement of the tool toward said edge, and means for imparting a swift hammer-like axial movement to the tool in the direction of the rivet, said means including spring means normally urging the tool in the direction of the rivet, manually operable means engaging the tool for moving the latter in the opposite direction and compressing said spring, and means for disengaging said manually operable means from said tool whereby the latter may perform its working stroke under the influence of said spring.

6. A device for flanging hollow rivets comprising a guide member, a riveting tool axially movable in said guide member and having a lateral projection for engaging and flanging a portion of the free edge of the rivet at each axial movement of the tool toward said edge, and means for imparting a swift hammer-like axial movement to the tool in the direction of the rivet, said means including spring means normally urging the tool in the direction of the rivet, manually operable means engaging the tool for moving the latter in the opposite direction and compressing said spring, means for disengaging said manually operable means from said tool whereby the latter may perform its working stroke under the influence of said spring and means for adjusting said disengaging means with relation to the manually operable means for varying the length of the working stroke of the tool.

7. A device for flanging hollow rivets comprising a guide member, a riveting tool and a carrier therefor axially movable in said guide member, said tool having a lateral projection for engaging and flanging a portion of the free edge of the rivet at each axial movement of the tool toward said edge, manually controlled means for imparting a swift hammer-like movement to the tool in the direction of the rivet, and means actuated by said manually controlled means to impart a rota-

tional movement to the tool at each axial movement thereof away from said edge to render said projection operative upon successive portions of said free edge.

5. 8. In a device for flanging hollow rivets comprising a guide member, a carrier axially movable in said guide member, a riveting tool carried by the carrier and having a lateral projection for flanging a portion of the free edge of the rivet at each axial movement of the tool toward said edge, spring means normally urging the carrier to move the tool towards the rivet, manually controlled trip means for compressing said spring and subsequently releasing the carrier, whereby the tool may perform its working stroke under the influence of said spring, means detachably securing said tool in said carrier, a member normally disposed adjacent said projection and displaceably mounted in said carrier, spring means enclosed by said carrier and normally retaining said displaceably mounted member in operative position, a sleeve-like member in said carrier forming an abutment for said spring means and removable from said carrier to facilitate removal of said member, and means externally of said carrier for effecting displacement of said member with relation to said tool.
